UNITED STATES PATENT OFFICE.

EDGAR B. HAMMOND, OF NEW BEDFORD, MASSACHUSETTS.

TACKLE-BLOCK.

SPECIFICATION forming part of Letters Patent No. 699,518, dated May 6, 1902.

Application filed February 10, 1902. Serial No. 93,427. (No model.)

To all whom it may concern:

Be it known that I, EDGAR B. HAMMOND, a citizen of the United States, residing at New Bedford, in the county of Bristol, State of Massachusetts, have invented certain new and useful Improvements in Tackle-Blocks, of which the following is a specification.

This invention consists in a tackle-block of improved construction.

10 The objects of the invention are to produce a block of strong and simple construction and which can be quickly taken apart and put together for the purpose of cleaning, repairing, and for changing its connections or fittings.

15 The purposes of the invention will be more fully stated in connection with the following detailed description.

Referring to the accompanying drawings, Figure 1 is an edge view, and Fig. 2 is a side view, of an improved tackle-block constructed in accordance with my invention. Fig. 3 is a section on the line A A of Fig. 1. Fig. 4 is an inside and Fig. 5 is an outside view of the combined strap and lining. Fig. 6 is an 25 inside view of one of the cheek-pieces, and Fig. 7 is a section on the line B B of Fig. 4.

As illustrated in the drawings, my improved tackle-block comprises two metal parts *a*, each comprising a strap and a lining-plate, an intermediate sheave *b*, having bearings in the straps, and a pair of cheek-pieces *c*, which are preferably constructed of wood, hard rubber, or other light and durable material. Each of the straps *a* has a central outwardly-projecting bearing 1 for the sheave-axle 2. They are also provided with inwardly-projecting bosses 3 4, which are connected by screws 5 6 when the parts of the block are assembled. The bosses 3, and likewise the bosses 4, abut 35 against each other and form shackles, to which hooks, ropes, or other fixtures may be connected. The straps are also provided with inward projections 7 below the upper shackle, which abut and form an eye 8.

40 To each strap 9 is connected a lining-plate 10, which is coextensive with the cheek-pieces *c*. About the lining is a marginal flange 11, which forms a finish and protection for the cheek-piece and also holds it against lateral 45 movement.

The cheek-pieces *c* have plain convex surfaces on their outer sides, without any rivets,

screw-holes, or other blemishes. This construction greatly enhances their appearance and permits of their being scraped without 55 dulling or nicking the scraping-tools. The cheek-pieces are fastened in place by screws 12, inserted from the inside of the linings. The cheek-pieces are provided with projecting portions 13, which fit within the recess 14 60 between the straps 9 and the marginal flanges 11. They overlap the flanges 11, so that said flanges do not show in side elevation. (See Figs. 1 and 7.) They are also provided with circular recesses 15, into which the bearings 65 1 fit. The recesses are preferably made somewhat deeper than the bearings and are provided with disks of felt or other fabric 16 to hold lubricating material for the sheave.

In some sizes of blocks I prefer to make the 70 linings 10 of stamped sheet metal and attach them by screws or rivets to the straps. In other cases, as shown in the drawings, the straps and linings are cast in one piece. It will be seen that all the parts of my improved 75 block can be separated very quickly by simply taking out the screws 5, 6, and 12 and as quickly put together. This permits of the parts being easily repaired and cleaned, and also permits of attaching any desired fitting 80 to the block or changing the attachments at any time.

It will be seen that certain features of my invention are applicable to blocks having two or more sheaves—as, for instance, the 85 mode of attaching the cheek-pieces. Roller-bearings may be provided for the sheave by simply enlarging the bearing-rings 1 sufficiently to admit the rollers between the axles 2 and the bearings.

Having thus described my invention, what I claim, and desire to secure by Letters Patent, is—

1. A tackle-block comprising the straps, the sheave having bearings in the straps, the 95 lining-plates connected to the straps, and the cheek-pieces connected by inside fastening to the lining-plates and having unbroken outer surfaces.

2. A tackle-block comprising a pair of 100 straps, a sheave having bearings in the straps, lining-plates connected to the straps, marginal flanges about the lining-plates, and cheek-pieces having unbroken outer surfaces,

said cheek-pieces fitting within the marginal flanges and being connected to the lining-plates by screws inserted from the inner surface thereof.

- 5 3. A tackle-block comprising the sheave, straps having outwardly-projecting bearings for the sheave, lining-plates connected to the straps, and cheek-pieces upon the outer surface of the lining-plates, said cheek-pieces
10 having unbroken outer surfaces and having recesses to receive the sheave-bearings and pads of lubricating material in said recesses.
4. A tackle-block comprising straps having

inwardly-projecting bosses 3, 4, connected by screws 5, 6, a sheave mounted in bearings in 15 said straps, lining-plates connected to the straps, and cheek-pieces connected to the lining-plates by inside fastenings, said cheek-pieces having unbroken outer surfaces.

In testimony whereof I affix my signature 20 in presence of two witnesses.

EDGAR B. HAMMOND.
